(57) **CLAIM**

The ornamental design for a safety light, as shown and described.

DESCRIPTION

FIG. 1 is a front perspective view of a safety light according to the present invention.

FIG. 2 is a back perspective view of the safety light of FIG. 1.

FIG. 3 is a front view of the safety light of FIG. 1.

FIG. 4 is a back view of the safety light of FIG. 1.

FIG. 5 is a right side view of the safety light of FIG. 1.

FIG. 6 is a left side view of the safety light of FIG. 1.

FIG. 7 is a top view of the safety light of FIG. 1; and,

FIG. 8 is a bottom view of the safety light.

The broken lines shown in the drawings illustrate portions of the safety light that form no part of the claimed design.
